Fig. 7.

UNITED STATES PATENT OFFICE.

JAMES NORTNEY, OF NEW ALBANY, INDIANA, AND FRANK SCHEFOLD, OF PARKERSBURG, WEST VIRGINIA.

ELECTRIC-LAMP SUPPORT.

SPECIFICATION forming part of Letters Patent No. 532,391, dated January 8, 1895.

Application filed October 18, 1892. Renewed December 12, 1894. Serial No. 531,600. (No model.)

To all whom it may concern:

Be it known that we, JAMES NORTNEY, of New Albany, county of Floyd, and State of Indiana, and FRANK SCHEFOLD, of Parkersburg, county of Wood, and State of West Virginia, have invented certain new and useful Improvements in Electric-Lamp Supports, of which the following is a specification, reference being had to the accompanying drawings.

The object of our invention is to produce a support for electric lamps, that is especially for the heavy kinds, which are used for arc light currents; which is readily attachable and detachable; and which automatically switches the current through the lamp, or around it as the lamp is connected or disconnected from the support.

Heretofore, owing to the want of an electric switch, except such as require special manipulation, the trimming and repairing of arc lamps have been usually performed when the current is on. By the use of our invention the lamp may be attended to at any time, day or night, whether the current is on or off without danger to the operator, and without interfering with the other lights in the circuit.

In the accompanying drawings, Figure 1 is a front elevation of our device complete, showing an arc lamp suspended as in use by two hooks; Fig. 2, a side elevation of the same. Fig. 3 is an enlarged view of the fixed or stationary part of the support; and Fig. 4, a similar view of the detachable parts showing one of the hooks partly in cross section. Fig. 5 is a side elevation of the switch support, showing the switch in position for passing the current around the lamp. Fig. 6 is a side view, partly in cross section of one of the hooks in the upright or locked position. Fig. 7 is a view similar to that shown in Fig. 5, showing the frame for the support in cross section, and the switch as in position for passing current through the lamp. Fig. 8 is a view similar to that shown in Fig. 6, showing the hook in the open, unlocked, or tilted position.

Referring to the figures on the drawings, 1 indicates a fixed or stationary frame that is hung from any suitable support, and is

adapted to carry a lamp in the elevated position for use.

2 indicates a lamp, and 3 its top plate.

4 indicates ropes or lines fastened to the top-plate 3, and adapted to raise or lower the lamp, pulleys 5 and 6 being provided for convenience.

The parts just described are of the ordinary and usual kind.

7 indicates a plate of electrical conducting material, such for instance as copper, which is securely fastened to the non-conducting bottom of the frame. Upon top of the plate 7 is fastened, by means of screws for instance, a fixed support 8, which is provided with a wrist 9, and preferably on the outer side with 65 a binding post 10. This support should always be a good conductor. Near the opposite end of the plate 7 we provide perforations 11, 12, 13, which preferably have their sides covered with suitable insulating material. 70 Where the bottom of the frame 1 is made of wood, as in practice it usually is, a special and additional insulation may be dispensed with.

14 indicates a movable support, or switch support we will call it, which is in all respects identical with the fixed support 8, but is provided with a stud 15 which projects from its base, and in length is preferably nearly double the width of the arm of the frame 1. It is 80 provided with a head 16 which affords a bearing for the spring 17 that is seated at its lower end against the top of the frame 1 when the stud has been passed through the perforation 11 in the plate 7 and bottom of the frame 1. 85 The tendency of this spring is to keep the switch support at all times in contact with the plate 7; but it allows those parts to become separated when sufficient weight is attached to the support to overcome the resistance of 90 the spring. To limit the downward movement of the switch support under vertical pressure we provide suitable stop pieces 18, which may be conveniently made of screws passed through suitable holes in the base of 95 the switch support and screwed into the bottom of the frame 1, being passed through the holes 12 and 13 in the plate 7.

As above explained, if the bottom of the frame 1 is made of wood, and the holes 12 and 13 are sufficiently large to prevent contact between their sides and the screws 18, that will be sufficient for the purposes of our invention; but as a matter of precaution the space between the sides of those holes and the screws may be filled with non-conducting material. The space between the sides of the hole 11 and 10 the stud 15 may also be treated in the same manner.

19 indicates a binding-post, similar to the one carried on the fixed support.

To the plate 3 of the lamp are firmly fixed, 15 by screws or other suitable means, hook frames 20, substantially alike in all respects, and are in practice set at such distance apart as when brought into juxtaposition with the frame 1, to be opposite the fixed support on the bottom 20 thereof. Each one of the hook supports is provided with parallel plates 21, which have corresponding vertical slots 22 adapted to receive pins 23 upon opposite sides of each of the hooks 24, so as to allow the hooks, under certain 25 conditions, to oscillate freely, and to be susceptible of a certain vertical motion. Beneath each of the hook supports, in suitable bearings, we provide a sliding plate 26, having an aperture 27 adapted to receive a pin 30 28 projecting from the bottom of the hook.

29 indicates a plate at right angles to the sliding plate, preferably made by bending or casting the sliding plate in that shape, which serves as a bearing at one end for a spring 30, 35 which is seated at its opposite end against the side of the top of the lamp, a recess 31 being provided therein for the reception of the spring, as illustrated.

32 indicates a thumb-piece for shoving the 40 sliding plate in opposition to the resistance of the spring. It will appear from an inspection of the drawings that the tendency of the spring is to operate the sliding plate in such a position as to keep the aperture 27 covered 45 by the base of the hook-support. So long as the sliding plate remains in this position, the hook is free to turn upon its pivot, and having its pivot pins, in practice, set forward of its medial line its tendency, when unrestrained, is to fall backward, as illustrated 50 in Fig. 8. If, however, the sliding plate is pushed forward until the aperture 27 is brought underneath the medial vertical plane of the slots 22, and in line with a pocket 33 55 provided in the top of the lamp and the hook carried in the elevated position and depressed, the pin 28 on the bottom of the hook will enter the aperture, restrain the backward movement of the sliding plate, and the hook will 60 be locked in the upright position. The only force which can release the hook is a vertical pull upon it, which will lift its pivot pins in the slots 22, free the pin 28 from the sliding plate, and allow it to oscillate freely thereon, 65 as before described.

34 indicates a curved guide piece secured

in front of each of the hooks, as for example by a bolt 35 in the hook support.

In practice the operation of our device is as follows: Suppose a lamp to be in position, as shown in Fig. 2, and a current to be passing from the wires through the binding posts 10 and 19, the fixed support and switch supports, and the hooks into the lamp to light it. If now it is desired to gain access to the lamp 75 for any purpose, the operator will pull upon the line 4 and draw the lamp up toward the fixed frame 1. Thereupon, as above explained, the hooks, under their own weight, fall backward, as illustrated in Fig. 8 of the drawings, and leave the lamp ready to be let down. Simultaneously with the elevation of the lamp, the spring 17 will operate to elevate the switch support and bring it in contact with the plate 7; whereupon, without any 85 interruption the electrical circuit will be established through the said plate. When the operator wishes to reset the lamp in position he pushes the sliding plates 26 in the position illustrated in Fig. 6 of the drawings and lifts 90 the hooks until the pins 28 enter the aperture 27 in the sliding plate, and the parts are set in the fixed position, as above described. Then by pulling upon the line 4 the lamp is elevated until the hooks are brought opposite 95 the supports, when the wrists 9 thereon, pressing between the curved guide piece and the ends of the hooks, will tilt the hooks slightly against the resistance of the spring 30, and allow them to hook over the wrists. Thereupon, tension upon the line being relieved, the weight of the lamp will operate to lift the hooks vertically and separate them from the sliding plates, leaving the lamp to swing freely, and ready to operate, as above described in 105 the first instance. At the same time the weight of the lamp will depress the switch support in opposition to the force of the spring 17, separate it from the plate 7, and re-establish a circuit through the lamp.

We do not confine ourselves to the details of construction herein illustrated and described, because they may be in many ways varied without departing from the scope of our invention.

What we claim is—

1. The combination with a lamp adapted to be hung to a support provided with suitable sustaining pieces, of pivoted hooks upon the lamp adapted normally to tilt open when released from the sustaining pieces, substantially as specified.

2. The combination with a lamp, of hooks pivotally secured thereto, and locking mechanism for temporarily holding the hook in a 125 fixed position, substantially as specified.

3. The combination with a lamp, of a loosely pivoted hook thereon, a curved guide piece and yielding locking mechanism for holding the end of the hook against the guide piece, 130 substantially as specified.

4. The combination of a plate, of a hook

support provided with slots, a hook pivotally mounted in the slots, locking mechanism for temporarily retaining the hook in a fixed position, whereby the hook may be set in one position and detached therefrom by moving it in its pivot slots, substantially as and for the purpose specified.

5. The combination with a plate, of a hook support, a hook pivoted in the slots therein, a guide-piece, a spring-actuated sliding plate in said plate adapted to engage with and hold the hook in a fixed position, substantially as set forth.

6. In supporting mechanism, the combination of a fixed plate and a supporter thereon, of a movable plate and hook thereon pivotally carried in vertical slots, of yielding locking mechanism adapted to hold the hook while in the lower parts of the slots, whereby the hook may be elevated against the supporter and snapped upon it and be released from the locking mechanism by the weight of

the movable part upon the hook, substantially as set forth.

7. In an electric lamp support, the combination with the fixed part carrying a fixed support and a movable support adapted by its movement to make and break circuit with the fixed support, of a lamp provided with a pair of vertically movable pivoted hooks electrically connected with the lamp to operate it, yielding locking mechanism for retaining the hooks temporarily in a fixed position, guide pieces in front of the hooks to latch the hooks upon the supports when pressed against them, all substantially as and for the purpose specified.
